(57) **CLAIM**

The ornamental design for a flashlight, as shown and described.

DESCRIPTION

FIG. 1 is a front view of the flashlight showing my new design;

FIG. 2 is a rear view thereof;

FIG. 3 is a left view thereof;

FIG. 4 is a right view thereof;

FIG. 5 is a top view thereof;

FIG. 6 is a bottom view thereof;

FIG. 7 is a front perspective view thereof;

FIG. 8 is a rear perspective view thereof;

FIG. 9 is a bottom perspective view thereof;

FIG. 10 illustrates an alternative mode of the flashlight of my new design;

FIG. 11 is a rear view of the alternative mode of the flashlight;

FIG. 12 is a left view of the alternative mode of the flashlight;

FIG. 13 is a right view of the alternative mode of the flashlight;

FIG. 14 is a top view of the alternative mode of the flashlight;

FIG. 15 is a bottom view of the alternative mode of the flashlight;

FIG. 16 is a front perspective view of the alternative mode of the flashlight;

FIG. 17 is a rear perspective view of the alternative mode of the flashlight; and,

FIG. 18 is a bottom perspective view of the alternative mode of the flashlight.

The broken lines show portions of the claim which form no part of the claimed design.

1 Claim, 18 Drawing Sheets
